Application March 25, 1932, Serial No. 601,158

14 Claims. (Cl. 164—112)

This invention relates to improvements in type setting systems and apparatus therefor and especially in perforators and counters which may be utilized for preparing a perforated tape for automatic control of composing machines of the linecasting type.

More particularly the invention relates to an improvement in adjustable stop mechanisms employed in connection with indicating mechanisms in keyboard perforators and counters, for example, as shown in copending application Serial No. 601,172 filed March 25, 1932 by H. L. Krum et al. The present device is particularly adaptable to indicators utilizing dials with which 15 the range of movement of the index hand varies within certain predetermined limits.

The primary object of the present invention is to provide an adjustable stop device which of itself is movable within a small range, but which 20 provides adjustability within a wide range.

In the preferred embodiment herein disclosed the present invention is used with a keyboard device intended to be employed in the preparation of perforated tapes, the perforations in which 25 represent lines of composed matter; and also to take account of the number of characters or matrices composed so that in a line of predetermined length the amount or length of a line remaining to be filled or composed will always be 30 ascertainable. For this purpose an indicator is provided which is adjusted for operation for lines of various lengths, the adjusting means of the present invention being applicable thereto, to define the range of movement of the index hand. 35 The movement of the index hand is controlled through a counting mechanism which is variably operated in accordance with the widths of the characters composed in the line, the operation of the counting mechanism being controlled, by a 40 series of keys arranged similar to the familiar typewriter keyboard, through the instrumentality of a selector mechanism contained within the base of the keyboard device.

The counting mechanism shown includes a 45 single unit wheel, and an escapement means has been provided to control the movement of the unit wheel in varying amounts to correspond to the thickness of the character composing the line. The indicating means comprises a sectoral or fan 50 shape indicator, the indications of which are controlled by the unit wheel as well as by a space key, the cooperative effect of this dual control being to indicate to the operator the approach of the end of the line.

55 A better understanding of the invention may

be had from the following description, taken with the accompanying drawings, wherein:

Fig. 1 is a perspective exemplification of an embodiment of the device according to the invention.

Fig. 2 is a fragmental rear elevational view of the dial shown in Fig. 1 illustrating in detail the device of this invention.

Fig. 3 is a front elevational view of the dial embodying the present invention.

Fig. 4 is a sectional view of the index hand release means.

Fig. 5 is a perspective view of a keyboard perforator and counter employing the device of the present invention.

Fig. 6 is a perspective representation of the counting mechanism utilized in the apparatus shown in Fig. 5.

Fig. 7 is an elevational view of the counting mechanism illustrating its operative positions.

Fig. 8 is a fragmental front elevational view of the indicating mechanism utilized in the machine shown in Fig. 5.

As is commonly known in the typographical art, composing machines of the linecasting type 80 are provided with matrices which consist of small brass units carrying indented characters in their edges and which are of different thicknesses due to the fact that the characters vary in width. Thus when these matrices are assembled into a 85 line of predetermined length the number of matrices necessary to complete the line varies with the particular matrices used, the length of the line therefor is dependent, not upon the number of matrices in the line, but rather upon the 90 thickness of the characters or matrices making up the line. Consequently, it is necessary during the preparation of a perforated tape representing lines of composed matter to totalize the various thicknesses of matrices corresponding to 95 the code perforations made in the tape so that the operator will be apprised at all times of the length of line remaining as each key is operated and can thus judge of the justifiability of the line, and upon determination that the 100 line composed is justifiable, the index hand is returned to its initial position against the adjustable stop provided by this invention, which has been adjusted to suit the length of line.

Besides the usual character matrices, composing machines of the particular type to which the present invention relates are also provided with expandible spacebands or spacers, or justifying matrices as they are sometimes called, which comprise a portion analogous to and hav-

60

65

70

75

80

85

90

95

100

105

110

- ing the contour of a character matrix and which is positioned in the line of matrices usually between each series of character matrices comprising a word, and this portion has slidably 5 articulated thereto and depending therefrom a wedge-shaped portion. By means of these wedge portions the spacers are adjusted between certain ranges of thickness before the casting operation is performed.
- 10 In order to accomplish the accurate counting or totalizing of the matrices or characters in the composed line the keyboard device shown in Fig. 5 is adapted to count proportions, and not actual dimensions. Thus, the apparatus can 15 be used for any size of type, provided only that the character in the various fonts of type have the same unit groupings, and an interchangeable spaceband segment be chosen to suit the set size of the font of type. The unit of width used 20 as a basis of measurement is called an "em", and the proportions mentioned above are expressed in eighteenths of the em or set size, since it has been found desirable to divide the em quad, which is equivalent in width to the widest 25 character into eighteen (18) units, and to establish eleven definite groupings, on the basis of the following unit size: 6 to 15 inclusive, and 18. Thus, for example, a lower case "a" would be assigned to group 11 regardless of the font 30 or style of type, signifying that a lower case "a" is eleven units in width; a unit being not an actual dimension but merely a proportion of the quad or set size of the particular font of which it is a part.
- 35 Since the disclosure herein set forth is in the nature of an improvement of keyboard perforators and counters disclosed in the aforementioned application, only so much of the mechanism of said application will be described as is necessary to an understanding of the present invention.
- 40 To control the variable movement of the unit wheel of the counting mechanism or device for counting or totalizing the thickness of the matrices composed in the line, the selector mechanism therefor is selectively controlled by a key 11 (Fig. 5) in the manner described in detail in the aforementioned co-pending application. Briefly, the depression of a key 11 actuates an associated 45 key lever 12, which in turn operates a code bar individual thereto to effect through a set of selector bars arranged transversely thereof the actuation of a corresponding selector lever 13 shown in Fig. 6. Disposed above each lever 13 and in 50 cooperative relation therewith is a transfer lever 14 (only one being shown in Fig. 6) which is pivotally articulated to a stop bar 15. As clearly described in the aforementioned application the series of transfer levers 14 are actuated simultaneously toward the levers 13 upon the energization of the transfer magnet 16 (Fig. 5), and the selected transfer lever 14 is rocked in a counter-clockwise direction, as viewed in Fig. 6, to move its associated stop bar 15 toward the left so that 55 the left hand extremity thereof is introduced into the path of a unit rack 17.
- 60 The unit rack 17 is slidably mounted on a unit rack slide 18 and is adapted to be interlocked in slidable relation therewith by a guide member 19 riveted to the slide. Disposed above the unit rack 17, Fig. 6, is a unit wheel 21 which is rotatably fixed on an operating shaft 22. In the present device a single operating shaft 22 is provided on which the unit wheel 21 is mounted, as 65 well as other operating parts necessary to control

the various functions of the device. This operating shaft serves with its associated parts as a mechanical interconnection between the counting mechanism and the indicating mechanism, as clearly set forth in the aforementioned application. As indicated in Fig. 5 there is mounted on the operating shaft 22 and frictionally connected thereto a gear 23 adapted to be in mesh with a pinion 24 affixed to the armature shaft of a motor 25. Gear 23 is adapted to rotate constantly and thus through its frictional connection to the shaft tends to impart constant rotation to the shaft 22. By reason of its frictional relation to gear 23 the unit wheel 21 also constantly tends to rotate. However, its rotation is controlled normally by a pawl member 26 and the unit rack 17; one or the other of said members being in engagement with the unit wheel 21 during the counting operation. Briefly, during the counting operation the pawl 26 and unit rack 17 are operated so as to bring 90 rack 17 into engagement and pawl 26 out of engagement with unit wheel 21 substantially simultaneously (a slight overlap being provided to prevent the escape of the unit wheel), the effect being to permit the unit wheel 21 to carry the unit rack 17 toward the right (as viewed in Fig. 6) until it is arrested by a selected one of the stop bars 15, at which time pawl 26 is again brought into engagement and rack 17 out of engagement with unit wheel 21 substantially simultaneously to prevent further rotation of unit wheel 21 while unit rack 17 returns to its original position.

Having reference to Figs. 6 and 7 it will be noted that the rotation or escapement of unit wheel 21 is controlled by the aforementioned unit rack 17 and the pawl member 26. As previously described the unit rack 17 is slidably carried on the unit rack slide 18 which is pivotally carried on bracket 27 integral with the base of the device. The unit rack 17 is provided with a pair of lugs 110 28 and 29. The right hand lug 28, as viewed in Fig. 6, cooperates with the stop bars 15, while the left hand lug 29 co-acts with a spring actuated return lever 31 pivotally mounted at 32 to a bracket 33. The tension of a spring 34 which actuates the return lever 31 is adjustable by means of a screw 35 mounted in bracket 33.

Pawl member 26 is pivotally mounted at 36 on a bracket 37 and tends to rotate in a counter-clockwise direction (as viewed in Fig. 6) due to the action of a spring 38, one end of which is secured to the upper extremity of the pawl member 26, and the other end being attached to a spring slip 39. Pawl member 26, which is provided with a toothed portion 41, thus is held in engagement with the teeth on the unit wheel 21 by means of spring 38. A stop 42, however, is provided whereby the degree of engagement between the toothed portion 41 and the unit wheel 21 may be controlled; that is, it is desirable to prevent the teeth in the pawl member 26 from bottoming when they engage with the teeth in the unit wheel 21 to preclude damage thereto from wedging.

Depending from pawl member 26 is a portion 43 which is provided with a laterally disposed end 44 (Fig. 7) adapted to cooperate with the extremity of the unit rack slide 18. The pawl member 26 is also arranged with an arm 45 to the outer end of which is pivotally connected one end of link 46, the other end of which is pivotally connected to the end of lever 47, which in turn is pivoted at 48 to the slide member 18. The opposite end of lever 47 is pivotally connected to arm 49 of operating lever 51 which is pivotally supported at 52 to the 140 145 150

bracket 37. Operating lever 51 is also provided with two arms 53 and 54. At the extremity of arm 53 is carried a follower roller 55 which co-acts with the cam 56. A follower roller 57 is also carried at the extremity of arm 54 of the operating lever 51 and is adapted to cooperate with a pair of cam portions 58 and 59 diametrically opposed to each other and which are secured to the face of the cam 56. Cam 56 is provided with two 10 similar cam surfaces, since two complete operations are performed during one complete revolution of the cam; that is, for one complete operation the shaft and cam are permitted to rotate one-half revolution thus enhancing the speed of 15 operation of the apparatus.

Upon the initiation of the rotation of cam 56 the follower roller 55 is acted upon by the periphery of the cam 56 so as to impart clockwise rotation to the operating lever 51. Arm 49 of the operating lever 51 thus is raised and in so doing lever 47 is caused to rotate about its pivotal connection with link 46 thus elevating the pivot 48 between the lever 47 and the unit rack slide 18. Slide 18 thus is elevated so as to bring the unit 20 rack 17 into engagement or mesh with the unit wheel 21. The continued rotation of the operating lever 51 in a clockwise direction, due to the conformation of the cam, causes the lever 47 to rotate about its pivot 48 as a fulcrum, in which 25 event the link 46 is given a downward movement which in turn imparts a clockwise rotation to the pawl member 26 about its pivot 36 against the action of spring 38. The lateral portion 44 of the pawl member 26 is now disposed beneath 30 the end of the unit rack slide 18, as indicated in dotted lines in Fig. 7, to insure, during the ensuing operation of the escapement means, the interengagement of pawl 26 with unit wheel 21 prior to the disengagement of rack 17 to preclude 35 the undue escapement or movement of unit wheel 21 which would otherwise be liable to occur. In effect, the portion 44 performs the function of a 40 safety device.

The unit wheel 21, which constantly tends to 45 rotate by virtue of being fixed to shaft 22, is thus released for rotation and the unit rack 17 being free to move is carried toward the right until the lug 28 is intercepted by one of the stop bars 15. At this point the cam portion 58 acts upon 50 the follower roller 57 so as to suddenly reverse the direction of rotation of the operating lever 51. The unit rack slide 18 cannot at this time be lowered because of the engagement of its forward extremity with the lateral portion 44 of the 55 pawl member 26. Therefore lever 47 is caused to rotate in a counterclockwise direction about the pivot 48 to cause the link 46 to be elevated, which in turn permits pawl member 26 to rotate in a counterclockwise direction, due to the action of 60 its spring 38, into engagement with the unit wheel 21, simultaneously causing the withdrawal of lateral portion 44 from engagement with slide 18.

The continued rotation of the operating lever 51 in a counterclockwise direction, due to the con- 65 tour of the cam, now causes the lever 47 to rotate about its pivotal connection to link 46 in a counterclockwise direction to withdraw the unit rack 17 from engagement with the unit wheel 21. The unit rack is thereupon placed under the influence 70 of the spring actuated return lever 31 (Fig. 6) and is carried toward the left thereby to its stop 61. The stop 61 is adapted to be cushioned by a compression spring 62 as indicated in Figs. 6 and 7.

To enhance the speed of operation of the apparatus herein described an escapement mech-

anism is provided whereby the amount of rotation of the operating cam 56 to effect a complete cycle of operation is limited to 180° or one-half revolution; thus, as previously indicated the cam 56 is provided with two similar cam surfaces.

80

The rotation of the shaft 22 is controlled by an electromagnetically operated escapement means shown in Fig. 5. The stop disc 63 is provided on its periphery with two diametrically opposed teeth (only one of which is shown in Fig. 5), since two complete operations are performed for each complete revolution of the disc 63. As set forth in the aforementioned application the stop disc 63 and the cam 56 are integral with a common sleeve member so that they function as a unit. When the escapement magnet 64 is energized momentarily its armature 65 is attracted and released, thus causing the escapement pawl 66 integral with the armature to effect the release or escapement of the stop disc 63 in known manner.

85

The indicating mechanism is illustrated in Figs. 1 to 5 inclusive. Fixed to the extremity of the operating shaft 22 opposite to the unit wheel 21 is a pinion 67 (Figs. 1 and 4) which is adapted to mesh with a gear 68 mounted on the stud shaft 69. The rotation of pinion 67 in variable amounts is controlled by the counting mechanism, previously described, and the rotation thereof is transmitted through gear 68 to an index hand or pointer 71. As indicated in Fig. 4 the gear 68 is provided with a hub and is rotatably mounted on the stud shaft 69 fixedly mounted on a bracket 72, Figs. 1 and 4. Stud shaft 69 carries axially therethrough a rod 73, the lower extremity of which, as viewed in Fig. 4, is provided with an integral flange, and the opposite end, as viewed in Fig. 1, is provided with a threaded portion.

90

The stud shaft 69 is flanged at its outer end thus forming a suitable journal for the gear 68 and is securely attached to the bracket 72 by means of a nut 74 and a locknut 75. A friction disc 76 is carried at the end of the rod 73 (Fig. 4) adjacent to the flange on said rod, which disc 76 is provided with a slot 77, more clearly shown in Fig. 2, adapted to receive a pair of diametrically opposed ears 78 and 79, integral with the hub of gear 68. The disc 76 thus is rotatable with the gear 68. Interposed between the disc 76 and the flange 81 integral with the hub of gear 68 and adapted to fit over the ears 78 and 79 is the index hand or pointer 71. Pointer 71 is normally held clamped between the disc 76 and flange 81 due to the distended action of a helical compression spring 81 carried on the rod 73.

95

The pressure exerted by the spring being varied by the adjusting nut 82, Fig. 1, the pointer 71 is adapted to be rotated correspondingly with the gear 68. A magnet 83 suitably mounted in the bracket 72 is provided with an armature lever 84 which carries at one end an adjusting screw 80 which is arranged substantially in axial coincidence with the rod 73. The screw 80 is normally held in abutting relation with the rod 73 by means of a spring 85 operatively connected to the armature 84. The adjustment just described is 100 provided so that when the electromagnet 64 is energized the attraction of the armature 84 effected thereby will cause the movement of the rod 73 against the action of the spring 81 an amount sufficient to insure the relaxation of the pressure between disc 76 and flange 81 to permit the pointer 71 to return to its initial position 105 against the adjustable stop provided by the present invention.

110

Having further reference to Fig. 1 it is seen 115

120

125

130

135

140

145

150

- that bracket 72 is provided with a vertical portion 86 on which is adjustably supported a sectoral or fan shape indicator dial 87, more clearly shown in Figs. 2 and 3. The dial 87 is pivotally held by 5 a collar nut 88 (Fig. 1) about which it is rotatable, the amount of rotation of which is limited by a slot and screw adjustment, not shown. As indicated in Figs. 2 and 3 the pointer 71 is provided at its outer extremity with a reverted portion 10 89 adapted to fit over and move along the arcuate edge of the dial 87. As shown in Fig. 3, the dial 87 is provided adjacent its arcuate edge with a scale or series of graduations representing "ems", the unit of type measure, and fractions thereof. 15 The reverted end 89 of the pointer 71 moves along this edge of the dial from left to right, towards zero, in response to the totalization or accumulation of the matrices or character thicknesses by 20 the counting mechanism, in the manner previously described.
- The annular pivotal portion of the pointer 71, as clearly shown in Fig. 2, is provided on a part of its peripheral edge with a series of projections 91, adjacent ones of which are oppositely 25 deflected to form a pulley-like groove to receive a flexible cord 92, one end of which is attached to the pointer as shown in Fig. 2 and the other end is secured to the extremity of a spring actuated pointer return lever 93 (Fig. 1).
- 30 It is obvious, therefore, that when the magnet 83, Fig. 1, is energized to effect the removal of the pressure of spring 81 from disc 76, the pointer 71 will be free to rotate in a clockwise direction as viewed in Fig. 1, due to the urge of return spring 35 94 until it is arrested by the adjustable stop 95 of the present invention.
- The lines of composition must necessarily vary in length to suit the width of the column of composed or printed matter into which they are to be 40 inserted; therefore, it is customary to provide a stop which is movable along a slot or guideway which stop forms a return point for the pointer or index hand 71. This point does not represent the zero position of the line, but instead represents the ultimate or limiting width of the line. 45 The distance, then, from the stop to the zero point represents the permissible range of movement of the pointer for a predetermined length of line. Thus, the pointer 71 moving from left to right 50 (Fig. 3) indicates, by its distance at any instant from the zero point marked on the gauge, the amount of line remaining to be filled, and when the pointer reaches the zero point, or approximately thereto, it is released and spring-returned 55 to the original position to begin its movement in accordance with a new line.
- It is manifest that an ordinary stop means must of necessity be movable between limits corresponding to the maximum range or length of line 60 of which the dial is capable of indicating and in effect, corresponds to the full width of the dial. However, in the adjustable stop device 95 of the present invention, which of itself is movable within a small range, but provides adjustability 65 within a wide range, a stop is provided, as indicated in Fig. 2, which comprises a substantially Y-shaped portion 96 of the ends of the arms 97 and 98 of which are provided with laterally disposed lugs 101 and 102, respectively. The stem portion 70 103 is provided near its extremity with a pair of laterally disposed portions 104 and 105 adapted to fit snugly into an arcuate slot 106 in the dial 87. The stem portion is also provided intermediate the lugs 104 and 105 with a threaded hole to receive a thumb screw 107 (Fig. 75

3), the shoulder of which is adapted to span the slot 106 so that the tightening of the screw 107 will effect a clamping means for the stop member and permit its adjustability.

At the fork of the Y portion formed by the arms 80 97 and 98 there is pivoted a stop member 108 adapted to swing between the limiting lugs 101 and 102. Stop member 108 is provided with the integral stud 109 against which the pointer 71 is adapted to strike. The prime purpose of providing such an adjustable stop is to permit of a wide range of adjustability with a minimum length of slot 106, thus preserving the rigidity of the dial.

When a maximum length of line is used, the member 108 is swung around to abut stop lug 102, and the adjustable stop 95 is moved in this condition toward the left as viewed in Fig. 3 so that the stop pin 109 aligns radially with the extreme left graduation. It is apparent that the end of the slot which is considerably inside of this point does not impair the strength or rigidity of the dial. Likewise, when a short line is to be used, the arm 108 is swung around to engage lug 101 and the adjustable stop 95 is moved in this condition toward the right (Fig. 3) so that for a minimum 100 length of line the stop pin 109 will be considerably in advance of the right end of the slot, thus preserving the metal between the right end of the slot and the edge of the dial.

It is well known in the typographical art that 105 the amount of possible justification in any assembled line of matrices is determined by the number of spacebands or spacers contained in it. As previously mentioned a spaceband comprises a matrix-shaped portion in which is slidably carried a wedge portion. The expansibility of the spaceband is determined by the difference between the thin end and the thick end of the wedge portion. Thus in order that the spaceband may be effective to justify a line, the difference between the aggregate or totalized thicknesses of the matrices in the line and the predetermined length of line must be equal to or less than (preferably the latter) the aforementioned difference in thickness, or expansibility of the spaceband; 110 so that, when the wedge portion is slidably moved along the matrix-shaped portion, which is held in alignment with the rest of the matrices in the line, it will tend to "fill up", as it were, the space left between the last matrix and the limiting 115 gauge representing the length of line. So, too, a similar result will be obtained when two or more spacebands have been included in the line; in which event the spacebands will be effective to justify the line when the difference between the 120 totalized thicknesses of the matrices and the length of line is less than the sum of the differences in thickness, or expansibility of the spacebands.

In the manual operation of a composing machine, the keyboard operator may watch the assembly of the matrices and spacebands in the assembling elevator, and thus personally determine the justifiability of the line. However, in the automatic operation of a composing machine by means of perforated tape the justification must be predetermined.

As previously set forth, the reverted end 89 of the pointer 71 moves along this edge of the dial from the adjustable stop 95 toward zero, in response to the totalization of the matrix or character thicknesses by the counting mechanism. Thus, the distance from the pointer 71 to zero indicates the amount of space left in the line to be filled with matrices, when the line contains

80

85

90

95

100

105

110

115

120

125

130

135

140

145

150

no spacebands. However, when spacebands are inserted in the line, the space remaining to be filled varies with the number of spacebands inserted. So, to indicate the justifiability of the composed line a pair of pointers 111 and 112 are provided, the distance between the pointers 111 and 112 indicating the cumulative amount of expansibility of the spacebands. Since the distance from zero on the scale to pointer 112 represents the sum of the thin edges of all the spacebands (whether one or more) in the line, and the distance from zero to pointer 111 represents the sum of the thickest ends of the spacebands, it is manifest that the distance between pointers 111 and 112 represents the difference between these sums, which is the amount of expansion or expansibility of the spacebands contained in the line. Therefore the space left in the line to be filled, when spacebands are inserted, is represented by the distance between the pointer 71 and any point between pointers 111 and 112. So, whenever the pointer 71 has entered the space defined by the pointers 111 and 112 the operator knows that the line he has just composed is justifiable.

To effect the differential movement of the pointers 111 and 112 toward the left (from the zero position) the mechanism indicated in Fig. 8 is provided. Rotatably carried on a stud shaft 113, which is mounted on the portion 86 of bracket 72 in axial coincidence with rod 73 (Figs. 2, 3 and 4), are the pointers 111 and 112. Referring again to Fig. 8, pointers 111 and 112 are provided with segmental gear portions 114 and 115, which are adapted to mesh with segmental gears 116 and 117, respectively, pivoted on the stud 113 mounted in the bracket portion 86. Integral with the gear 116 is a ratchet segment 119. Gear 117 is provided with a slot and screw adjustment 121 and is constrained thereby to move with the gear 116. Gears 116 and 117 and ratchet 119 normally tend to rotate in a counterclockwise direction (as viewed in Fig. 8) due to the action of a spring 122 distended between the gear 116 and the base.

The ratchet 119 cooperates with a pawl 123 pivotally attached to the space keylever 124 which is pivotally articulated to the space bar 125, similar to that used on ordinary typewriters, as shown in Fig. 5. The depression of the space keylever 124 imparts a corresponding downward movement to pawl 123, which is yieldingly held into engagement with the ratchet 119 by a spring 126 secured to a suitable guide member 127. Each time the space keylever 124 is operated or depressed the ratchet 119 is actuated against the action of its spring 122 a distance equal to one ratchet tooth, and a corresponding movement is imparted to pointers 111 and 112. The gearing 114 to 117, inclusive (Fig. 8), is so chosen as to impart a differential movement to pointers 111 and 112, such that each time the ratchet 119 is stepped one tooth, pointer 112 will be moved a distance corresponding to the thin end of the spaceband and pointer 111 will be moved a distance corresponding to the thick end of the spaceband. Furthermore, the pitch of the teeth of ratchet 119 is chosen to suit the size of spaceband employed or utilized with the set size of the font of type used, and hence members 116, 117 and 119, being integral, may be rendered interchangeable.

A detent 128 cooperates with ratchet 119 and pawl 123 to prevent the ratchet from slipping back when the pawl 123 is moved into engagement

with a succeeding tooth, thus maintaining the pointers 111 and 112 in their newly selected position.

It is manifest that the present invention provides an adjustable stop means which of itself requires a minimum amount of movement and which at the same time provides a maximum amount of adjustability; which device preserves the rigidity and strength of the dial with which it is utilized. The employment of the present adjustable device obviates the need of unnecessarily cutting away the dial in order to provide adjustability commensurate with the possible maximum amount of indication of which the dial is capable. With the use of an ordinary stop means, the length of guideway cannot possibly be equivalent to the possible maximum amount of indication without substantially increasing the size of the indicator dial. By means of the present invention the size of the dial is greatly reduced and its resistant qualities are preserved. Furthermore, the present device may readily be used in connection with the justification indicating means, and together they assist in providing a compact keyboard counting device.

Although the present invention has been disclosed in connection with a keyboard counting mechanism, it is, of course, understood that the invention is capable of embodiment in many forms other than that specifically disclosed without departure from the spirit and scope of the invention as defined in the appended claims.

What is claimed is:

1. In an indicating device, a dial, an index member, means to move said index member relatively to said dial, and means for stopping said index member, movable integrally within a small range and including a dually positionable element to provide adjustability within a wide range.

2. In a keyboard device, a counting device, a series of keys, an indicating device, means for variably operating said counting device in accordance with the operation of said keys to control the operation of said indicating device, said indicating device including an index member movable variably in accordance with the operation of said counting device, and a stop device for said index member which is movable integrally within a small range and includes a dually positionable element to provide adjustability within a wide range.

3. In a keyboard device suitable for the production of perforated tape representative of consecutive characters and word spacers, a counting device, a series of keys, an indicating device, means for variably operating said counting device in accordance with the operation of said keys to control the operation of said indicating device, said indicating device including an index member movable variably in accordance with the operation of said counting device, a pair of pointers, a special key for controlling the actuation of said pointers different amounts for each effectiveness thereof for indicating the cumulative expansibility of the word spacers, and an adjustable stop device including a dually positionable member adapted to cooperate with said pointers to define the permissible range of movement of said index member.

4. In a keyboard device suitable for the production of perforated tape representative of consecutive characters and word spacers, a counting device, a series of keys, an indicating device, means for variably operating said counting device

- in accordance with the operation of said keys to control the operation of said indicating device, said indicating device including an index member movable variably in accordance with the operation of said counting device, a pair of pointers, a special key for controlling the actuation of said pointers different amounts for each effectiveness thereof for indicating the cumulative expansibility of the word spacers, and an adjustable stop device including a dually positionable member adapted to cooperate with said pointers to define the limits of a justifiable line of characters. 5
5. In a keyboard device suitable for the production of perforated tape representing justifiable lines of matrices, a plurality of members movable under different operating conditions, a series of keys, means operated upon the depression of each of said keys for effecting the movement of one of said members an amount predetermined by the 10 particular key depressed, a special key, means actuated by said special key for controlling the movement of the others of said members differentially according to the number of times said special key is depressed, and an adjustable stop device including a dually positionable member adapted to cooperate with said last mentioned members to define the permissible range of movement of said first mentioned member indicative of a justifiable line of matrices. 15
6. In a keyboard device suitable for the production of perforated tape representing justifiable lines of matrices, a plurality of keys, a counting device comprising a single unit wheel, means to rotate said unit wheel variable amounts according to the keys depressed, an indicator dial, an index hand, said index hand operable variably to correspond with the operation of the unit wheel, a special key, a pair of pointers, means controlled by said special key to move said pointers proportionally each time said special key is depressed, and an adjustable stop device including an extension member adapted to cooperate with said pointers to define the permissible range of movement of said index hand indicative of a justifiable line of matrices. 20
7. In a keyboard device suitable for the production of perforated tape representing justifiable lines of matrices, a plurality of keys, a counting device comprising a single unit wheel, means to rotate said unit wheel variable amounts according to the keys depressed, an indicator dial, an index hand, said index hand operable variably to correspond with the operation of the unit wheel, a special key, a pair of pointers, means controlled by said special key to move said pointers proportionally each time said special key is depressed, and an adjustable stop device including an extension member adapted to cooperate with said pointers to define the limits of a justifiable line of matrices. 25
8. In combination with a keyboard perforator suitable for the production of perforated tape representative of consecutive characters and expansible word spacers, a plurality of keys, a counting device comprising a single unit wheel, means to rotate said unit wheel variable amounts according to the keys operated, an indicator dial, an index hand, said index hand operable variably to correspond with the operation of the unit wheel, a spacer key, a pair of pointers, means controlled by said spacer key to move said pointers differentially to correspond to the increment of expansibility provided by a spacer each time said spacer key is operated, and an adjustable stop device including an extension member adapted 30
- to cooperate with said pointers to define the permissible range of movement of said index hand. 9. In combination with a keyboard perforator suitable for the production of perforated tape representative of consecutive characters and expansible word spacers, a plurality of keys, a counting device comprising a single unit wheel, means to rotate said unit wheel variable amounts according to the keys operated, an indicator dial, an index hand, said index hand operable variably with respect to said dial to correspond with the operation of the unit wheel, a spacer key, a pair of pointers, means controlled by said spacer key to move said pointers differentially to correspond to the increment of expansibility provided by a spacer each time said spacer key is operated, and an adjustable stop device movable integrally within a small range and providing adjustability within a wide range adapted to cooperate with said pointers to define the permissible range of movement of said index hand. 35
10. In combination with a keyboard perforator suitable for the production of perforated tape representing justifiable lines of matrices, a scale, an index member movable variably with respect to said scale to show the totalized width of matrices in the line at any time, a pair of pointers movable variably with respect to said scale to show the amount of justification possible in the line at any time, and a stop device movable integrally within a small range and providing adjustability within a wide range adapted to cooperate with said pointers to define the limits of a justifiable line of matrices. 40
11. In combination with a keyboard perforator suitable for the production of perforated tape representing lines of composition, a member movable under certain operating conditions, a pair of members operable under other operating conditions, and means movable integrally within a small range and adapted to provide adjustability within a wide range cooperative with said pair of members to define the effective range of movement of said first mentioned member. 45
12. In combination with a keyboard perforator suitable for the production of perforated tape representing lines of composition, a scale, a pointer movable variably with respect to said scale to indicate the cumulative widths of characters, a pair of pointers, a gear train from a common source of power for rotating said pair of pointers different distances for each effectiveness thereof for indicating a different condition, and an adjustable stop device including an extension member adapted to cooperate with said pair of pointers to determine the permissible range of movement of said pointer. 50
13. In a keyboard perforator suitable for the production of perforated tape representative of consecutive characters and expansible word spacers, a counting device, an indicating device including an index member, a mechanical interconnection between said devices including a single shaft, motive means mounted on said shaft, a constant torque imparted to said shaft by said means, selector mechanism individual to said counting device, escapement means cooperative with said motive means and said mechanism to effect the selective operation of said counting device to actuate said index member correspondingly to indicate the cumulative widths of characters, a pair of pointers, a gear train from a common source of power for rotating said pair of pointers proportionally for each effectiveness thereof to indicate the cumulative expansibility 55

of the word spacers, and means movable integral-
ly within a small range and adapted to provide
adjustability within a wide range cooperative
with said pair of pointers to define the effective
range of movement of said index member.

14. In an indicating device, a dial, an index
member, means to move said index member rela-
tively to said dial to indicate a certain condition,
a pair of pointers, means to move said pair of

pointers proportionally to indicate another con-
dition, and means movable integrally within a
small range and adapted to provide adjustability
within a wide range cooperative with said pair of
pointers to define the effective range of move- 80
ment of said index member.
